^{Inventor}
William D. Johnston

By Joshua A. Morris

Attorney

UNITED STATES PATENT OFFICE.

WILLIAM DANIEL JOHNSTON, OF WACO, TEXAS, ASSIGNOR TO WM. CAMERON & CO. INC., OF WACO, TEXAS, A CORPORATION OF TEXAS.

DESIGN FOR A WALL CABINET.

Application filed November 4, 1927. Serial No. 23,998. Term of patent 14 years.

To all whom it may concern:

Be it known that I, WILLIAM D. JOHNSTON, a citizen of the United States, residing at Waco, in the county of McLennan and State of Texas; have invented a new, original, and ornamental Design for a Wall Cabinet, of which the following is a specification, reference being had to the accompanying drawing, forming part thereof.

In the drawings—

I claim:

The ornamental design for a wall cabinet, as shown.

WILLIAM DANIEL JOHNSTON.
